INVENTOR, BY
Louis Fisher Lee,
Atty's.

UNITED STATES PATENT OFFICE.

TRACY MINER METCALF, OF ST. PAUL, MINNESOTA.

TICKET-HOLDER.

SPECIFICATION forming part of Letters Patent No. 324,869, dated August 25, 1885.

Application filed March 2, 1885. (No model.)

To all whom it may concern:

Be it known that I, TRACY MINER METCALF, a citizen of the United States, and a resident of St. Paul, in the county of Ramsey, 5 in the State of Minnesota, have invented certain new and useful Improvements in Ticket-Holders, of which the following specification is a full, clear, and exact description, reference being also had to the accompanying drawings, in which—

Figure 1 is a front view, Fig. 2 is a side view, and Fig. 3 is a plan view, of the holder open. Fig. 4 is a plan view of a double-folding holder closed. Fig. 5 is a perspective view, enlarged, of one of the ticket-holding frames or racks. Fig. 6 is an enlarged perspective view of one of the springs removed from the rack.

A' A² are oblong frames of wire, each having a bar, A⁴, connecting their ends centrally. Attached by their ends within these frames A' A² and between the frames and bars A⁴ are a series of oblong frames, a, arranged alternately in the frames A' A², as shown in Fig. 1, so that the smaller frames a in the larger frame A' will be opposite the spaces between the smaller frames a in the larger frame A² when the two frames A' A² are folded over face to face.

Between the frames A' A² is another frame, A³, to which the frames A' A² are hinged at b, as shown, the frame A³ thus serving to keep the frames A' A² some distance apart when they are folded over face to face, as shown in Fig. 4, and as hereinafter more fully described. Embracing each of these small frames a are two bands, d' d², their fronts bent off at right angles at d³ d⁴, and thence downward again and attached to the ends of the frames a, as shown in Fig. 5, the frames a, bands d' d², and sections d³ d⁴ thus forming small frames or racks open at the ends, and having small spaces e between the ends of the bands d' d² and the points where the sections d³ d⁴ branch from them, as shown.

B are coiled springs attached to the bands d' d² of each rack, and each spring provided with a cross-bar, g, at its top.

C represents the tickets, which will be inserted into each rack from one end between

the springs B and the outer portions of the bands d' d², the spring thus holding the tickets pressed outward and preventing them from falling from the racks.

The spaces e will be a trifle wider than the thickness of one ticket, but less than the thickness of two tickets, so that only one ticket at a time will be removed from the racks.

As before stated, and as shown in the drawings, the racks are arranged alternately, so that when the frame A² is folded over upon the frame A', or vice versa, the racks attached to one frame will fit into the spaces between the racks on the other frame, so that the racks and frames will occupy only one-half as much space when thus folded together as they would occupy were the racks all opposite each other.

By this simple arrangement means are provided for holding in plain view of the ticket-seller, and in a very easily accessible position, a large number of tickets, while at the same time, when not in use, the frames can be folded up into convenient shape for placing in a safe or other secure place.

The frames A' A² will be provided with means for suspending them from hooks or nails on the wall when in use.

This device will generally be used in selling railroad-tickets, but may be used for other similar purposes.

The bars g across the springs B are an important feature of my invention, as they increase the size of the holding-surface of the springs and prevent the tickets tilting upon the springs.

Any number of the frames A' or A² and their attached racks may be connected together, as may be desired, and any desired number of the racks may be arranged in each frame.

In Figs. 1, 2, and 3 I have shown two sets of the frames and their racks, and in Fig. 4 I have shown four sets, the two sections being hinged together at h and resting back to back.

In Fig. 2, at i, one of the tickets is shown partially removed to illustrate the manner of removing the tickets from the racks.

Having described my invention and set forth its merits, what I claim is—

1. In a ticket-holder, a frame, A', having

ticket holding racks attached thereto, a similar frame, A^2 , having similar ticket holding racks attached thereto, the racks of one frame alternating with the racks of the other frame, and an intermediate frame, A^3 , hinged to said frames A^1 A^2 , whereby the latter may be folded together and the racks of one frame fit into the spaces between the racks of the adjoining frame, substantially as and for the purpose set forth.

2. The combination of the frames a , bands

d^1 d^2 , corner sections d^3 d^4 , open spaces e , springs B , and cross-bars g , substantially as and for the purpose set forth.

In testimony whereof I have hereunto set my hand in presence of two subscribing witnesses.

TRACY MINER METCALF.
